UNITED STATES PATENT OFFICE.

THOMAS J. MURPHY, OF NEW YORK, N. Y.

JUNCTION-BOX.

SPECIFICATION forming part of Letters Patent No. 614,882, dated November 29, 1898.

Application filed April 22, 1895. Renewed December 31, 1897. Serial No. 665,255. (No model.)

To all whom it may concern:

Be it known that I, THOMAS J. MURPHY, a citizen of the United States, residing at New York city, in the county and State of New York, have invented a certain new and useful Improvement in Junction-Boxes, of which the following is a specification.

Heretofore junction-boxes have been made which from their mode of construction were not secure against fire risks and which were expensive in construction.

The object of my invention is the production of a cheap and simple junction-box which is especially adapted for use in connection with systems of electrical conduiting for interiors and which will be safe from fire risks occurring within the box as well as from leakages of current.

In the accompanying drawings, forming part of this specification, Figure 1 is a plan view of a junction-box embodying my invention with the cover removed. Fig. 2 is a cross-section thereof on the line 2 2 of Fig. 1 with certain of the parts removed. Fig. 3 is a longitudinal section taken on the line 3 3, Fig. 1. Fig. 4 is a detail of a nipple to which the conduits are attached. Fig. 5 is a modified form of box. Fig. 6 is a longitudinal section thereof through the line 6 6, Fig. 5. Fig. 7 is another form of box. Fig. 8 is a longitudinal section thereof on the line 8 8, Fig. 7. Fig. 9 shows a box with the cover in place and without nipples, and Fig. 10 is a cross-section thereof on the line 10 10.

A is the wooden casing of the box, which serves to receive the lining B. This lining is of a refractory non-conducting material and to its use the box owes its chief advantages. I prefer slate, as at once fulfilling the objects named and at the same time being cheap. As shown in the section Figs. 2 and 3, the bottom of the box, as well as the sides thereof, is lined with this refractory non-conducting material. A cover also lined with the same material is to be used with this box, so that the whole interior of the box is made thereof. In Figs. 5, 6, 7, 8, 9, and 10 I have shown this simple form of slate-lined box. In those figures, C represents the seat for the door, which is formed by the top edge of the slate lining of the box.

In Figs. 1, 2, and 3 is shown what I call my

"double slate-lined box"—that is to say, I take the box already described and within it form another box D of the same refractory and insulating material—as, for instance, slate, as shown—by preferably providing a bed-block of slate E, surrounded by the four walls, (lettered D,) as shown in Figs. 1 and 3 particularly. This double slate-lined box is particularly advantageous for the room it affords within which to make the distribution of the conductors. The electrical binding-posts, safety-fuses, or other electrical appliances used in boxes of this nature are mounted upon the slate base E, as shown, or in any suitable manner.

In order to fit the box for use with the tubes used in electrical interior conduiting, I provide a short piece of pipe F, threaded, as shown, and pass it through the wooden frame A, which frame is countersunk on the side next the slate lining, and place a washer G on the threaded pipe within the recess. The outer end of the short section of screw-threaded pipe receives another washer H, as shown more particularly in Fig. 4, these washers serving to keep the pipe in place. It is obvious that a threaded conduit-pipe might be secured directly to the projecting nipple or a suitable protecting-coupling used to secure the said pipe to the nipple. By this arrangement instead of passing the conduit-pipe directly into the interior of the box, where it might be difficult to make the connection, the connection is made on the outside, where there is usually ample room to work. Again, by this arrangement I avoid weakening the slate lining to a great extent, for the reason that I do not need to bore the same to the extent of the full outside diameter of the conduit-tube, for by the arrangement shown the nipple F projects against the slate lining, and it is necessary only to provide an opening in the slate lining large enough to take therethrough the conductors I, which opening of course is only about as large as the interior diameter of the nipple.

It will be observed that when a box is completely lined with slate or other refractory non-conducting material in the manner I have described there will be absolutely no danger of leakages of current therefrom, and should there be any crosses, blowing of safety-fuses,

or short-circuits within the box any arcing resulting therefrom will be confined to the interior of the box and will not set fire to surrounding inflammable materials, nor will the 5 box be heated up by low-resistance crosses of long duration, as would a metal box without a similar lining.

I claim—

10 A box for mounting and connecting electrical conductors, comprising an exterior wooden shell, a lining of a refractory, non-conducting material therefor, a cover pro-

vided with a similar lining, and a screw nipple or nipples extending through said exterior wooden shell against the lining, said lining being countersunk and receiving a washer, with a washer on the outside of the wooden shell, all substantially as set forth.

This specification signed and witnessed this 20th day of April, 1895.

THOMAS J. MURPHY.
